[57] CLAIM

The ornamental design for a gate operator, as shown and described.

DESCRIPTION

FIG. 1 is a top, front, and right side perspective view of a gate operator showing my new design;

FIG. 2 is a top, rear; and left side perspective view thereof;

FIG. 3 is a top plan view thereof;

FIG. 4 is a front elevational view thereof;

FIG. 5 is a fragmentary vertical cross-sectional view thereof, taken along line 5—5 of FIG. 6;

FIG. 6 is a right side elevational view thereof; and,
FIG. 7 is a left side elevational view thereof.

The chain element is shown broken-away in the views to indicate indeterminate length.
